GRINDING MACHINE

Raymond A. Cole, Worcester, Mass., assignor to
 Norton Company, Worcester, Mass., a corpora-
 tion of Massachusetts

Application October 9, 1935, Serial No. 44,204

4 Claims. (Cl. 51—165)

The invention relates to grinding machines and with regard to its more specific features to a sizing mechanism therefor.

One object of the invention is to provide an electric sizing device of simple construction and dependable in operation. Another object of the invention is to provide a sizing device having no contact with a work piece. Another object of the invention is to provide an electric sizing device whose sensitivity is not affected by arcing. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which is shown one of various possible embodiments of the mechanical features of my invention,

Fig. 1 is a vertical transverse sectional view, showing the hydraulic actuating and control mechanism for the cross feed slide of a grinding machine, and illustrating also the caliper mechanism.

Fig. 2 is a fragmentary vertical sectional view, the section being taken on the line 2—2 of Fig. 1.

Fig. 3 is an electrical and optical diagram.

I provide a grinding machine including a machine base 10 having the usual ways 11, 12 for the support of a work table 13 upon which is supported a headstock and a tailstock, not shown, for the support and rotation of a work piece 14 which is to be exteriorly ground. The usual mechanism for traversing the work piece by longitudinal reciprocation may be provided, but so far as certain features of the invention are concerned the grinding may be by the so-called "plunge-cut" method, in which the grinding wheel advances relative to the work piece without relative traverse thereof, or with only limited reciprocation for the removal of grinding lines.

Mounted on the usual cross feed slideway, not shown, is a cross slide 15 of any usual or desired form having a wheel head 16 which journals in journals 17 the spindle 18 of a grinding wheel 19. The wheel 18 may have a wheel guard 20 of any usual or desired construction.

Referring now to Figs. 2 and 3, fastened to the inside of the machine base 10 underneath the table 13 are a pair of brackets 21, 21 supporting journals 22, 22 for a rock shaft 23 upon which is mounted optical apparatus generally indicated by the numeral 24. This optical apparatus

24 comprises a pair of parallel tubes 25, 25 opening into a rectangular box portion 26 at the bottom and capped by a plate 27 which has integrally fastened to it a central web 28 having a work receiving contour 29 and a front plate 30 and top plate 31, the plates 27, 30 and 31 being integral with each other and with the web 28. Extending downwardly from the bottom of the box 26 and integral therewith is a web 32 having a journal 33 integral therewith, through which journal 33 passes the rock shaft 23. Thus the optical apparatus 24 is supported by the machine base, and it may be adjusted in position parallel to the ways 11 and 12 and by moving the journal 33 along the shaft 23, and when a desired position of adjustment is attained the journal 33 is locked upon the rock shaft 23 as by means of a set screw 34, there being a hole 35 in the machine frame for access to the optical apparatus. In so much as the shaft 23 may always turn in the journals 22, the optical apparatus 24 may be swung back and forth and adjusted angularly around the axis of the shaft 23.

Extending downwardly from the journal 33 and preferably integral therewith is an arm 36 which is connected by means of a spring 38 to the machine base 10, the spring 38 serving to urge the entire optical apparatus 24 in a clockwise direction, Fig. 1. A screw 40 having a hand wheel 41 for convenient adjustment from the front of the machine constitutes an adjustable stop for the arm 36, by means of which the position of the optical apparatus may be delicately adjusted. For quick forward movement of the optical apparatus, however, it may be swung to the front of the machine by hand, and to hold it there while changing work pieces any desired latch or the like may be provided, such as the hook 42 and eye 43.

In the box 26 I provide a pair of electric light bulbs 45 which may be of the point of light type or of the ribbon filament type in order to produce a beam having as little stray light as possible within practical limits. In the box 26 is also a mirror 46 set at an angle of approximately 45° to the axes of the parallel tubes 25. In each tube 25 is a pair of condensing lenses 47, 48, and in plate 27 located in orifices 49 are concave lenses 50. The mirror 46, lenses 47 and 48, and lenses 50 may be made adjustable in the usual way, not herein shown in detail as constructions for lens adjustments and the like are well understood. Attached to the web 28 and extending from it on either side is a pair of supports 51 for convex lenses 52. Extending for

wardly from the plate 30 and suitably insulated are the conventional four-hole sockets 53 for the support of photoelectric cells 54 (only two of the prongs being electrically connected).

5 Referring now to Fig. 3, by the apparatus so far described a pair of converging light beams 55 and 56 are formed. These beams originate in the filaments of the lights 45, are reflected by the mirror 46 through the two pairs of condensing lenses 47 and 48, and the converging beams are spread to some extent by the lenses 50. However, between the lenses 50 and 52 I desire that the beams shall become crossing beams 57 and 58 with foci F in the horizontal plane of the axis 10 of the work piece 14. From the foci F the beams spread and are by the lenses 52 transformed into crossing beams 59 and 60 whose cross sectional area is approximately equal to that of the cathodes 61 of the photoelectric cells 54 at 15 that point.

20 The axes of the beams 55, 57 and 59 are parallel to each other and to the axes of the beams 56, 58 and 60. But I desire that the work piece 14 shall uncover them successively. The interval 25 between uncovering of the two beams is a matter of a few ten-thousandths of an inch, for example fifteen ten-thousandths of an inch (.0015''), and this may be achieved in many ways. For example, and referring to the lower part of Fig. 2, 30 the left-hand bracket 21 may have a portion 65 depending therefrom which includes a boss 66 through which passes a screw 67 controlled by a hand wheel 68. The brackets 21 have slots 69 and are held to the frame 10 by bolts 70 passing 35 through the slots 69, and by reason of the direction of elongation of the slot 69 the brackets may be adjusted in a horizontal direction, and preferably the shaft 23 is a shouldered shaft so that all play can be taken out of the parts when 40 the brackets 21 are adjusted and fastened in position. The left-hand end of the shaft 23 may be moved to the front of the machine by an amount sufficient to make the difference, in ten-thousandths of an inch, between uncovering 45 of the beams 57 and 58, by turning the hand wheel 68, which will spring the left-hand bracket 21 outwardly to a slight extent, or if this is not enough the lower bolts 70 may be slightly loosened.

50 Various expedients may be adopted to form a very narrow focus F for each beam. With the system of lenses shown and described, if the filament of each bulb 45 were a geometrical point the foci F would also be geometrical points except for color aberration. But a color filter may 55 be used in connection with the apparatus for more accurate results, and this color filter may be placed under the lowermost lenses 47. The focus F of each beam, however, is still an image of the lamp filament. Point-of-light electric 60 bulbs are now available, in which the luminous part is very small. I prefer to use such, but a ribbon filament light has a relatively small light source. However, the use of diaphragms, while they diminish the intensity of the light, may be 65 resorted to. A feature of the electrical apparatus about to be described is that, in conjunction with a photoelectric cell, it is quite sensitive and responds to a certain quantum of light, which while not absolute in the true sense is nevertheless 70 unvarying within practical limits of a few ten-thousandths of an inch in the size of the work piece, when used in connection with the apparatus of the invention.

75 In the preferred embodiment of the invention actuation of one photoelectric cell 54 causes cross

feed movement between grinding wheel 19 and work piece 14 to cease, while actuation of the other photoelectric cell 54 causes the cross slide 15 to retreat carrying the grinding wheel 19 definitely away from the work piece. Grinding between the first indication or electrical actuation and the final coming to size takes place owing to the pressures set up in the machine parts and such grinding, already known in connection with manually operated machines, has been 10 termed "sparking out". The invention is shown embodied in an external cylindrical grinding machine, and the first actuation in some cases may be a slowing down of the cross feed rather than an actual discontinuance of all movement. The 15 mechanism of the present invention may be adjusted so as to bring the cross slide 15 to a stop at the first photoelectric actuation, or it may be adjusted so as to decrease the rate of cross feed rather than to stop it altogether. 20

In the preferred embodiment of the invention I use a hydraulic cross feeding mechanism which may be readily controlled by solenoids actuated by the photoelectric cells 54. Referring again to Fig. 1, depending from the cross slide 15 is a 25 bracket 105 to which is attached a piston rod 106 having a piston 107 located in a cylinder 108. A slide valve 109 has reduced diameter portions 110, 111 and 112, which are separated by full diameter portions fitting a valve bore 113. A 30 port 114 connects to the right-hand side of the cylinder 108 while a port 115 connects to the left-hand side thereof. A passage 116 connects the port 114 with a valve port 118, and a passage 117 connects the port 115 with the valve 35 port 119. As shown in Fig. 1, the ports 118 and 119 are symmetrically located in the bore 113, one being slightly to the right of the center portion thereof, and the other an equal distance to the left. 40

The bore 113 also has ports 120, 121 and 122, the former being a fluid entrance port and connected to pipe 123 leading to a source of fluid under pressure, and the latter two being fluid exhaust ports, the port 121 being connected by 45 pipe 128 to a valve 124, and the port 122 being connected by piping 125 direct to the exhaust. The valve 124 is connected by piping 126 to the piping 125 as clearly illustrated.

The slide valve 109 may be operated manually 50 by means of a rod 130 having a handle 131 within convenient reach of the operator, and the slide valve 109 may be operated in one direction by means of a solenoid 132, as integrally formed with the slide valve 109 is a rod-like portion 133 55 which constitutes the core of the solenoid 132.

With the slide valve in the position shown in full lines in Fig. 1, fluid under pressure is admitted from the piping 123 through the port 121 and past the reduced portion 111 to the 60 port 118 and the fluid passes through passage 116 to the port 114 which is at the right-hand end of the cylinder 108 and therefore the fluid will urge the piston 107 to the left thus to move the cross slide 12 and carry the grinding wheel 65 15 towards and to reduce the diameter of the work piece 11. The parts are shown at the commencement of this operation in Fig. 1. While pressure fluid is moving the piston 107 to the left, fluid is being exhausted from the left-hand 70 side of the cylinder 108 and it flows outwardly by way of port 115, passage 117, and port 119 past reduced diameter portion 112 and through piping 128 to valve 124 and thence by way of pipe 126 into pipe 125 which connects with the 75

fluid sump or source of supply. When the valve 109 is moved to its right-hand position, as indicated in dotted lines in Fig. 1, the fluid under pressure from the pipe 123 and port 122 passes 5 by way of reduced diameter portion 111 to port 118 and by passage 117 to port 115 and thus into the left-hand side of the cylinder 108. This causes movement of the piston 107 to the right thus carrying the grinding wheel 15 away from 10 the work piece, and the fluid is forced out of the right-hand side of the cylinder 108, through port 114, passage 116, through port 118, past reduced diameter portion 110 to port 122 and by way of piping 125 to the sump.

15 It will be noted from the foregoing description that when the grinding wheel is traveling inwardly or to the left the exhaust fluid is passing through the valve 124, but when the grinding wheel is moving outwardly or to the right 20 the exhaust fluid does not pass through the valve 124. The valve 124 is an adjustable metering valve and may be set to stop position; thus it controls the advance of the grinding wheel and procures a slow feed thereof and it is capable of 25 being moved to a position to reduce the feed or to stop it altogether.

Considering now the construction of the valve 124 and referring to Fig. 1, the pipe 128 connects to a port 135 which opens into the side of a 30 cylinder 136. Opposite the port 135 is a port 137 connecting with the pipe 126. A close fitting piston 138 is located in the bore of the cylinder 136 and its movement to the left is controlled by an adjustable stop screw 139. Connected to the piston 138 by means of a rod portion 140 is another piston member 141. Another rod 142 passes into a solenoid 143 and constitutes the core thereof. A spring 144 surrounds the core rod 142 and urges the piston 141 and 40 therefore the other parts including the piston 138 to the left. The rod 142 is connected at 145 to a brass or other non-magnetic rod 146 which is in position to be engaged by a stop screw 147.

By properly setting the stop screw 139 as by 45 means of a hand wheel 148 the normal condition of the valve 124 may be determined. By setting the stop screw 147 as by means of the hand wheel 149 the condition of the valve 124 may be adjusted for such part of the cycle as involves the 50 energization of the solenoid 143.

According to the preferred embodiment of the present invention the machine has three main parts to a cycle of operation. There is first the infeed of the grinding wheel when the solenoid 143 is deenergized and the valve 124 is at its 55 adjusted open or widest open position. Then follows the grinding cycle while the solenoid 143 is energized, the piston 138 being to the right and either restricting the flow of fluid through 60 the valve 24 more than previously or else cutting it off altogether. Thirdly, there is the return of the grinding wheel to a retracted position which is not controlled by the valve 124 at all.

The change from the first to the second phase 65 of the grinding cycle is determined by one indication from the sizing apparatus and the change from the second to the third phase of the cycle is determined by a second indication of the sizing apparatus. As so far described the right-hand photoelectric cell 54 (Fig. 2) sets in motion the change from the first to the second phase and the left-hand photoelectric cell 54 sets in motion the change from the second to the third phase. The change from the third to the first 70 phase might be effected in any manner but so

far as the present embodiment is concerned may be effected by manual control, as a new work piece is to be introduced at this point, and the introduction of such work piece will deenergize the solenoids and the operator has ample time to 5 shift the rod 138.

It should be noted that either of the photoelectric cells 54 may be selected for initiating either change, as this is simply a matter of connection of two pairs of final circuit wires. Furthermore, the sizing apparatus may be adjusted so that the change from the first phase to the second phase occurs at the end of the movement which brings the grinding wheel against the work piece, or the change may be effected when 15 the work piece is nearly to size so that the final cuts will be in the nature of a fine grinding operation. I prefer to adjust the valve 124 so that no advance of the grinding wheel will take place after the solenoid 143 is energized, the further 20 reduction of the work piece being due to the strain or spring in the machine parts and the final cuts being what have been described as "dying out" cuts, or simply "sparking out". The 25 sparking out method of grinding has been found to be particularly effective for the production of true cylindrical fine finish and accurate work. The caliper mechanism of the invention may be readily adjusted so that the difference between actuations of the two photoelectric cells 30 is within the range of the amount of size reduction effected by a dying-out cut.

Referring now to Fig. 3, the right-hand photoelectric cell 54 is associated with amplifying and relay apparatus to energize the solenoid 143, 35 while the left-hand photoelectric cell 54 is associated with identical apparatus to energize the solenoid 142. Any amplifying and/or relay apparatus may be used, and direct or alternating current may be employed in any of the circuits, 40 as my invention is not confined to any particular electrical arrangement. For purposes of illustration, however, I have disclosed in Fig. 3 a set of circuits which may be employed.

Referring now to Figs. 3, a 110 volt A. C. line 45 155 has connected to it conductors 156 and 157 leading to the terminals 158 and 159 of a transformer primary 160. Similarly conductors 156a and 157a connect to terminals 158a and 159a of a transformer primary 160a. Three secondary 50 coils 161, 162 and 163 are energized by the primary coil 160 and similarly secondary coils 161a, 162a and 163a are energized by the primary coil 160a. Non-inductive potentiometer resistances 164 and 164a are connected across the conductors 165 and 166 and 165a and 166a respectively of the coils 161 and 161a. Conductor 165 leads to the anode 167 of the photoelectric cell 54 and conductor 165a leads to the anode 167a of the photoelectric cell 54. Conductors 166 and 166a 60 lead to condensers 168 and 168a which are connected by conductors 169 and 169a to conductors 170 and 170a which connect respectively to the cathodes 61 and 61 of the photoelectric cells 54. 65

The secondary coils 162 and 162a respectively 70 energize filaments 173 and 173a of amplifying or triode tubes 174 and 174a. Grids 175 and 175a of the tubes 174 and 174a are connected by conductors 176 and 176a to non-inductive resistors 177 and 177a the other ends of which are 75 connected to the conductors 170 and 170a respectively. Plates 180 and 180a in the tubes 174 and 174a respectively are connected to conductors 181 and 181a which conductors are connected to terminals 182 and 182a. The sec- 75

ondaries 163 and 163a have each of them one end thereof connected respectively to terminals 183 and 183a. Connected in parallel between terminals 182 and 183 are a condenser 184 and a sensitive relay coil 185, and connected in parallel between terminals 182a and 183a are a condenser 184a and a sensitive relay coil 185a. The other ends of the secondary coils 163 and 163a are connected to conductors 186 and 186a. Conductors 186 and 186a connect respectively to the movable elements 187 and 187a of potentiometers 164 and 164a and conductors 186 and 186a are also connected by leads 188 and 188a to the midpoints of coils 162 and 162a. It will now be seen that a certain degree of illumination of right-hand photoelectric cell 54 causes energization of relay coil 185, while a certain degree of illumination of left-hand photoelectric cell 54 causes energization of relay coil 185a. The apparatus is adjustable by means of the potentiometers 187-164 and 187a-164a.

In so much as the energization of the relays 185 and 185a may be momentary I further have provided a relay to close and keep closed the final circuits upon any energization whatsoever of the sensitive relays. As shown in Fig. 3, conductor 156 also connects to a terminal 190 and conductor 156a connects to a terminal 190a. Conductor 157 connects to a relay coil 191 and conductor 157a connects to a relay coil 191a. The other ends of the relay coils 191 and 191a are connected to terminals 192 and 192a respectively.

Pendulum contactors 193 and 193a are adapted to connect terminals 190-192 on the one hand and 190a-192a on the other hand. These pendulum contactors are arranged to be operated by long arms 194 and 194a of armatures 195 and 195a actuated by the coils 185 and 185a.

Energization of the relay coils 191 and 191a respectively, even momentary energization thereof, causes the closing of knife switches 197 and 197a. These are double knife switches and one set of terminals thereof is connected by shunt leads to the 110 volt A. C. wires 156, 157 and 156a, 157a, respectively, while the other terminals of these knife switches 197 and 197a connect to lines 200 and 200a which respectively lead to the solenoids 143 and 132.

The pendulum contactors 193 and 193a may be of spring steel so that normally they lie in the position shown in Fig. 3 but a slight force will throw them into contacting position. The photoelectric cell cathodes 61 and 61a are preferably sensitive caesium plated cathodes and a certain definite amount of light on either of them will cause enough current to flow in either of the relay coils 185 and 185a to close the circuit by contactor 193 and 193a. By producing narrow beams of light 57 and 58 and providing sensitive double relay apparatus one element of which is a current measuring relay, I am enabled accurately to size the work.

In order to set up the machine, a work piece 14 ground to the desired size by means of hand gauges is placed in the machine centers and the optical apparatus 24 is then moved towards the work piece to the full line position shown in Fig. 1. In this figure the apparatus is shown moved to the right as far as it will go and the smallest size of work piece 14 which can be gauged by a particular sizing apparatus according to the invention will cut off the beams of light. Both lamps 45 are lighted and the switches are closed. The hand wheel 41 should now be turned to the right and first the solenoid 143

will actuate and later the solenoid 132. As the solenoid 132 actuates the adjustment is finished. At this time the hydraulic motor is not operating at all.

A scale may be provided in connection with the hand wheel 68 and if the interval between actuations of the solenoids was not satisfactory, the hand wheel 68 may be turned and the trial gauging repeated. After this is done the trial work piece 14 is removed, and an oversized work piece is placed between the centers, and the switches again closed and the rod 130 is drawn toward the front of the machine. Many other manners of adjusting the machine and many varied cycles of operation may be adopted.

In this embodiment of the invention the optical apparatus 24 is shown attached to the machine base and it extends through a slot 201 in the table 13. This locates the sizing apparatus always opposite the grinding wheel. The slot 201 may be as long as the stroke of relative traverse between the wheel and the work piece.

In order to eliminate a light intercepting film of water upon the work piece I provide a wiper 202 which may be made of rubber or fibre or any other substance that will conform to the work piece and remove the major part of any water or other matter adhering thereto. It will be observed that the sizing apparatus of this invention leaves no scratch marks upon the work piece and may be quickly adjusted for different sizes of work pieces.

It will thus be seen that there has been provided by this invention an apparatus in which the various objects hereinabove set forth together with many thoroughly practical advantages are successfully achieved. As various possible embodiments might be made of the mechanical features of the above invention and as many changes might be made in the embodiment above set forth, it is to be understood that all matter hereinbefore set forth or shown in the accompanying drawings is to be interpreted as illustrative and not in a limiting sense.

I claim:-

1. In an external cylindrical grinding machine, means for holding and rotating a work piece to be ground, a grinding wheel, means for procuring a cutting advance between said means and said grinding wheel, a support for optical apparatus including a long tube, lenses in the tube, a light source at one end of the tube, a photoelectric cell fixed with relation to the support and located with respect to the light source and the lenses so that it will conditionally receive light from the source via the lenses, means for altering the cutting advance of the work piece, and amplifying means responsive to the photoelectric cell operating the means for altering the cutting advance, the support being so located with relation to the means for holding and rotating the work piece that an oversized work piece intercepts some of the rays from the light source and at a particular size of the work piece the photoelectric cell is energized.

2. In apparatus as claimed in claim 1, the combination with the parts and features therein specified of adjustment means to move the support to adapt the apparatus for different sizes of work pieces.

3. In apparatus as claimed in claim 1, the combination with the parts and features therein specified of a second set of instrumentalities comprising a long tube, lenses in the tube, and an additional photoelectric cell, constructed and operating as defined in claim 1, whereby to effect

dual control of the cutting advance to change from a coarse grinding operation to a fine grinding operation when one photoelectric cell is actuated and to cause cessation of grinding when the other photoelectric cell is actuated.

4. In apparatus as claimed in claim 1, the combination with the parts and features therein

specified of lenses so arranged with respect to the work piece holding and rotating means that the light is brought substantially to a focus with its rays tangent to the work piece at the critical size of said work piece when the photoelectric cell is 5 energized.

RAYMOND A. COLE.
